UNITED STATES PATENT OFFICE.

HENRY HOWSON, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

APPARATUS FOR DRYING CLAY BODIES.

Application filed July 21, 1920. Serial No. 397,807.

To all whom it may concern:

Be it known that I, HENRY Howson, a citizen of the United States, residing in Philadelphia, Pennsylvania, have invented 5 certain Improvements in Apparatus for Drying Clay Bodies, of which the following is a specification.

My invention relates to certain improvements in apparatus for drying clay bodies, 10 in which a cover is used to enclose the article to be dried.

The invention is an improvement on the apparatus set forth in the application filed by Joseph L. Buckley, May 26, 1920, under 15 Serial No. 384,427.

The object of my invention is to provide means for automatically operating the cover.

My invention is especially adapted for use in connection with carriers of an endless 20 conveyor located within a drying chamber. The invention also relates to certain details of construction which will be fully described hereinafter.

In the accompanying drawings:

25. Fig. 1 is a vertical sectional view of a portion of a drying apparatus illustrating my invention;

Fig. 2 is an enlarged sectional view showing one of the trays illustrating my improved cover;

30. Fig. 3 is a view illustrating the cover extending part way towards the bottom of the tray so as to prevent circulation of air in the space above the article to be dried;

35. Fig. 4 is a side view, partly in section, of a drying apparatus illustrating my improved cover and the mechanism for operating the cover at each end of the drier;

Fig. 5 is an enlarged sectional view illustrating in detail the cover shown in Fig. 4;

40. Fig. 6 is a view illustrating a modification of the invention;

Fig. 7 is a sectional view of one of the trays showing a detail of the construction of 45 the cover illustrated in Fig. 6; and

Fig. 8 is a sectional view of a portion of a drier and illustrating another modification of the cover in which the front is elevated simultaneously with the top section.

50. Referring in the first instance to Figs. 1 and 2 of the drawings, 1 is the casing of a drier of any suitable construction. 2 is an endless chain conveyor, which passes around sprocket wheels 3 within the drier. In

the front of the casing is an opening 4 55 through which the articles to be dried are passed in placing them on the trays. 5 is another opening in the casing through which the articles are removed from the 60 trays.

In the construction shown in Fig. 1, the dried articles are removed from the conveyer at the same end of the drier as the articles to be dried are inserted. This is also the case in the construction illustrated 65 in Fig. 8. In the construction illustrated in Figs. 4 and 6, the articles to be dried are inserted at one end and, when dried, are removed at the opposite end.

Carried by the conveyer 2 is a series of trays 70 6, preferably perforated, as shown, so that when the mold *a*, with the article *b* thereon, is placed on the tray, the air will circulate under the mold. At the rear of the tray is a vertical wall 7, in the present instance, 75 to which is pivoted at 8 a cover 9. This cover has a depending portion 10 at the front end so that when it is in the position illustrated in Fig. 2, the mold and the article mounted thereon is enclosed within the 80 cover. Projecting, in the present instance, from the rear of the cover is an arm 11 having a roller 12, which comes in contact with a rail 13 in the drier. On the tray is an arm 14 having a roller 15, which is 85 adapted to travel on a guide rail 16 so as to keep the tray in a horizontal position, as the cover is elevated by the roller 12 coming in contact with the rail 13.

The air can be circulated in the drier by 90 a fan 17, shown clearly in Fig. 4, and the air may be heated by pipes 18, or heated air may be introduced into the drying chamber without departing from the essential features of the invention. Any 95 suitable partitions may be used for causing a proper circulation of air.

I lay no claim to the circulating means, or the manner in which the conveyer is carried through the drying chamber. 100

Each cover is preferably made in the form of a frame carrying a plaster Paris, or equivalent, section 19, preferably located directly above the mold *a* and the article *b* thereon so that, while a certain portion of 105 the moisture is drawn from the article by the mold, moisture is also drawn from the article by the section 19 of the cover. As

the mold and this section are both porous, the circulation of heated air within the drier causes these parts to draw moisture from the clay article. The cover protects the article from the direct action of the heated air in circulation and also prevents the accumulation of dirt, or other foreign matter, on the article while being dried.

In Fig. 3, I have illustrated a construction in which the cover 9^a is pivoted at 8^a to the frame of the tray and the depending portions 7^a and 10^a of the cover extend to a point on a line with the edge of the mold a'. A felt, or other flexible, section 20 is secured to the cover in any suitable manner so as to rest upon the edge of the mold.

By this construction, the entire under side of the mold is exposed to the air in circulation, while the space between the mold and the under side of the cover is protected, as in some grades of ware it is desirable to protect the ware from the circulating air.

In Fig. 4, I have illustrated a construction in which the cover is automatically raised at the feed end of the drier and can be automatically raised at the discharge end of the drier. Mounted on the tray 6^c are two open bearings 21 for pivot rods 22 and 23 carried by the cover 9^c. The central portion of the cover 9^c is pivotally connected to the front and rear members 10^c and 7^c by the pivot rods 22 and 23. An arm 11^c, having a roller 12^c is adapted to travel in contact with a rail 13^c at the feed end of the drier and with a rail 24 at the discharge end of the drier. At the discharge end of the drier is a guide rail 16^c for a roller 15^c on an arm projecting from the tray.

By this construction, one end of the cover is raised so that as the trays pass the feed opening 4^c, the cover will be automatically raised and, after an article has been placed in position on the tray, the cover is automatically lowered so as to enclose the article. When the tray reaches the opening 5^c, the cover is again raised, but, in this instance, it is the opposite side of the cover that is raised, so that the article can be removed from the tray.

In Figs. 6 and 7, I have illustrated another modification, in which the cover is made in two parts 9^d and 9^e pivoted to a central bar 25 and a lever 11^d is pivoted at 26 and has a roller 12^d, which is arranged to come in contact with the rails 13^d and

24^d. When the lever 11^d comes in contact with the cam rails 13^d, it elevates the section 9^d of the cover so as to allow articles to be placed on the tray. When the tray reaches the delivery end of the drier, the lever is moved in the opposite direction by the rail 24^d and lifts the section 9^e. Both sections of the cover remain in the closed position as the cover travels through the drier.

In Fig. 8, I have illustrated a modification of the device illustrated in Fig. 2, in which the front end 10^e is pivoted to the body of the cover and has an arm 27, which comes in contact with a pin 28 on the side members of the tray so that as the cover is elevated this front member is raised in order to increase the space for the insertion or removal of the article to or from the tray.

While I have illustrated certain modifications of the invention, others will readily suggest themselves.

The conveyer may be driven by the ordinary means. A driving pulley may be mounted on any one of the shafts carrying the sprocket wheels.

I claim:

1. The combination in a drier, of a casing; an endless conveyer; means for driving the conveyer; a series of trays on the conveyer; a cover pivotally mounted on each tray; an arm projecting from each cover; and rails with which the arms come in contact so as to raise the covers.

2. The combination in a drying apparatus, of a casing; an endless conveyer; trays thereon; and a cover pivotally mounted above each tray, each tray being arranged to receive a mold and the article to be dried mounted thereon, the cover having depending extensions stopping short of the tray so as to enclose the article to be dried.

3. The combination in a drying apparatus, of a casing; an endless conveyer; trays thereon; a cover pivotally mounted above each tray, each tray being arranged to receive a mold and the article to be dried mounted thereon, the cover having depending extensions stopping short of the tray so as to enclose the article to be dried; and flexible extensions on the cover resting on the mold so as to prevent circulation of air in the space between the article to be dried and the cover.

HENRY HOWSON.
